Atty.

United States Patent Office.

J. J. McLANE, OF SAGETOWN, ILLINOIS.

Letters Patent No. 78,809, dated June 9, 1868.

IMPROVEMENT IN CHURNS.

The Schedule referred to in these Letters Patent and making part of the same.

TO ALL WHOM IT MAY CONCERN:

Be it known that I, J. J. McLANE, of Sagetown, in the county of Henderson, and in the State of Illinois, have invented certain new and useful Improvements in Churns; and do hereby declare that the following is a full, clear, and exact description thereof, reference being had to the accompanying drawings, and the letters of reference marked thereon.

Figure 1 represents a side elevation.

Figure 2, a horizontal section.

Figure 3, a view of the dasher, and its mode of connection to the box, and

Figure 4 represents a view of the dasher, with its arms placed in an angular manner.

In the annexed drawings, making a part of this specification, A represents a vessel, made with a curved bottom, and supported upon suitable legs.

The bottom of the vessel A is made of two bent plates of metal, and attached to the sides thereof, as shown, so as to make a chamber between them, in which cold or warm water may be poured, to regulate the temperature of the cream in the vessel A. A spout, f, leads into the chamber, between the bottom plates B and C, through which the water may be poured in or out.

D' D' represent shafts, made with a recess or dent in one end, in which the point of the set-screw g fits, and with a tongue or projection on the opposite end, to fit in the groove of the journal j.

The shafts D' D' are made just long enough to fit between the sides of the vessel A.

Paddles or agitators H H are loosely secured to the shafts D' D', for the purpose of agitating or churning the cream, by means of the sleeves or thimbles D.

h represents the journal-bearing, secured to one side of the vessel A, and made in the form shown, and j represents the journal, adjusted and fitting therein.

It will be seen that, when the shaft D' is adjusted with one end resting in the groove of the journal j, and pressed against the same by means of the set-screw g, said journal will make a perfect joint or valve, so as to prevent any leakage whatever.

The shaft D' is suspended and works on the journal j and screw g, which form the journals for said shaft.

L L represent gear-wheels, secured to and on the outer end of the journals j j, which mesh with and are operated by the wheel K, which is provided with a crank, to which the power to drive this machine is applied.

The agitators H H are loosely adjusted on the shaft D', so as to be set at any angle with each other, when they are tightened by means of a collar-nut on one end of the shaft D'.

Having thus fully described my invention, what I claim as new, and desire to secure by Letters Patent, is—

The arrangement of the box A, with metal bottom B C, two cross-shafts D D, having movable arms H H, and adjustable by the journals j and bearings h, the several parts being constructed and operating substantially as specified.

In testimony that I claim the foregoing, I have hereunto set my hand, this 21st day of March, 1868.

J. J. McLANE.
